UNITED STATES PATENT OFFICE.

DANIEL GRUHLKEY, OF MARSEILLES, ILLINOIS.

RAILROAD-SWITCH.

SPECIFICATION forming part of Letters Patent No. 679,225, dated July 23, 1901.

Application filed May 10, 1901. Serial No. 59,592. (No model.)

To all whom it may concern:

Be it known that I, DANIEL GRUHLKEY, a citizen of the United States, residing at Marseilles, county of Lasalle, and State of Illinois, have invented certain new and useful Improvements in Railroad-Switches, of which the following, when taken in connection with the drawings accompanying and forming a part hereof, is a complete and full description, sufficient to enable those skilled in the art to which it pertains to understand, make, and use the same.

This invention relates to certain improvements in switches for railroad-tracks of the class wherein the main-track rails are unbroken and the switch-track rails are moved laterally onto and over the main-track rails when the switch is to be used.

The object of this invention is to obtain a railroad-switch of the kind named which will be simple in construction and wherein the switch-track rails will be locked firmly in place to and on the main-track rails when the switch is thrown for use, a railroad-switch which is easily operated, durable, and not liable to get out of order when used, and one having few parts.

Figure 1 is a plan view of the switch embodying this invention; Fig. 2, a cross-sectional view on lines 2 2 of Fig. 1, viewed in the direction indicated by the arrows. Fig. 3 is a cross-sectional view on line 3 3 of Fig. 1, viewed in the direction indicated by the arrows. Fig. 4 is a side elevation of main-track rail at the toe of the switch and of the switch-rail forming such toe. Fig. 5 is a top plan view of the main rail and switch-rail shown in side elevation in Fig. 4. Fig. 6 is a cross-sectional view of such main track at the point thereof illustrated in Figs. 4 and 5 and a sectional view of the rail and crank-rod on the opposite side of the main track, as is shown by dotted line 6 6 in Fig. 1, viewed in the direction indicated by the arrows; and Fig. 7 is a perspective view of a portion of the crank-rod of the apparatus, showing one of the crank-arms thereof.

A reference-letter applied to designate a given part is used to indicate such part wherever the same appears throughout the several figures of the drawings.

R and R' represent the rails of the main

track, which rails are continuous and unbroken in the parts thereof upon which the switch is operated.

W and W' represent the switch-rails. Switch-rail W is pointed at the end thereof, forming the toe of the switch, as at X, Fig. 1. The switch-rail W' at the end thereof forming the toe of the switch is bent, as at X', Figs. 1, 4, and 5, and W² is an elevating-plate, preferably a steel plate of suitable shape, bolted to the side of rail W', as by bolts W³ W³, Figs. 3 and 5. The forward end W⁴ of elevating-plate W² is flattened to a chisel shape to lay flatwise on the main track and substantially cover the same the full width thereof when the switch is turned for use, so that a car-wheel entering the switch may roll thereonto without appreciable jar and be thereby elevated or raised to a height sufficient to allow the flange of such wheel to pass over the main track R' when the axle thereof is at, say, the place marked W⁵ in Figs. 1, 4, and 5 and pass from such elevating-plate onto the switch-rail W'.

Switch-rail W is divided or cut, as at W⁶, Figs. 1 and 3, and the two ends thus obtained, (lettered W⁷ and W⁸, respectively,) as also the end X of rail W and the end X' of the rail W', with elevating-plate W² thereon, are adapted to be moved laterally to or from the main rails R R'. The end W⁷ is bent to lie alongside the main rail R, as is shown in Fig. 2, and the sliding locking-block, herein-after described, moves adjacent thereto, holding such end in place on the main-track rail R' when the switch is turned for use, as is illustrated in the drawings. End W⁷ is cut away on the bent portion, as at W⁹, Figs. 1 and 2, so that a wheel worn to have a hollow tread cannot crowd ends W⁷ and W⁸ apart.

C is a crank rod or shaft located adjacent to and parallel with the main rail R on the outside of the main track and journaled in the boxes a a.

C', C², C³, C⁴, and C⁵ are crank-arms extending out from shaft C, such arms being duplicates but differently positioned on crank-rod C, as illustrated in Fig. 1, one of such crank-arms C³ being shown in perspective in Fig. 7.

S is the lever of the switch-stand, by means of which the switch-rails W W' are moved

and the locking-plates, hereinafter described, are actuated.

D', D², D³, D⁴, and D⁵ are connecting-rods, which are attached to the respective crank-arms C', C², C³, C⁴, and C⁵.

E is a bell-crank pivoted at e and slotted, as at E', to receive the upturned end d' of connecting-rod D'.

F is a longitudinally-movable plate slightly wedge-shaped and connected, by means of link G, to the bell-crank E so as to be moved longitudinally as such bell-crank is turned on its pivot e by the connecting-rod D' when crank-rod C is turned for the operation of the switch.

H is the base in which the locking-plate F moves, and h is a plate attached to one side of switch-rail W'. The plate h is preferably dovetailed, as is shown in Fig. 6 of the drawings, to hold the plate F thereto, whether such plate is positioned, locking switch-rail W' onto the main-track rail R', as is illustrated in the drawings, or whether the same is retracted, as when the switch is thrown open. Connecting-rod D² is attached to switch-rail W' to control the position of such switch-rail. Connecting-rod D³ is attached to the switch-rail W near the end W⁷ thereof, and such end W⁷ is held in place on the main-track rail R' in the same manner as the end of rail W' is held in place, as above described, (by locking-plate F and the connections thereof.)

E² is a bell-crank pivoted at e and provided with slot E'. F' is the locking-plate of end W⁷ of rail W.

G' is the connection between plate F' and pivotally-mounted bell-crank E², and H' is the base in which such locking-plate moves longitudinally. The upturned end d⁴ of connecting-rod D⁴ extends into slot E' of bell-crank E².

Connecting-rod D⁵ is attached to switch-rail W, as at d⁵, (near the end W⁸ of said switch-rail.)

Fig. 1 shows the switch set for use. By turning shaft C, as by lever S, the locking-plates F F' are retracted, ends X X' of rails W W' are moved laterally from the main-track rails R R', and ends W⁷ and W⁸ of switch-rail W are moved laterally from off the main-track rail R' by the longitudinal movement of the several connecting-rods D', D², D³, D⁴, and D⁵.

Having thus described my invention, what I claim as new, and desire to secure by Letters Patent, is—

1. In a railroad-switch, the combination with the main and unbroken rails of a railroad-track, of a switch-point rail cut at its crossing of the unbroken rail of the main track, means for moving the cut ends later-

ally in opposite directions and so that the tread thereof may move over and off of the main rail, a rigid plate, a sliding block between the rigid plate and the inner end of the 65 cut switch-point rail, a crank-rod and a connection between the crank-rod and the sliding block, whereby, when the cut ends of the switch-point rail are moved over and onto the main rail the sliding block is moved to lock 70 the switch-point rail with the end thereof adjacent thereto firmly in place on such main rail, and connections between the crank-rod and the toe of the switch-rails, whereby the position of such toe ends of the switch-rails 75 is determined by the crank-rod, and an elevating-plate attached to the inner side of the outside switch-point rail, adjacent to the toe thereof, a rigid plate, a sliding block and a connection between the sliding block and the 80 crank-rod; substantially as described.

2. In a railroad-switch the combination with an unbroken rail of the main track, of a switch-point rail the toe whereof is adjacent to and outside of the main rail, a rigid plate, 85 a sliding block between the rigid plate and the outside of the switch-point rail near the toe of such rail a crank-rod, connection between the crank-rod and the sliding block and between the crank-rod and switch-point rail 90 and an elevating-plate attached to the inner side of the switch-point rail adjacent to the toe thereof whereby when such toe is moved laterally by the movement of the crank-rod the elevating-plate is moved over and off of 95 the main rail and when over the main rail the movable block locks it in place thereon; substantially as described.

3. In a railroad-switch, the combination with the unbroken rails of the main track, of a switch-point rail cut at its point of crossing such unbroken main-track rail, means whereby the ends obtained by such cut may have lateral movement in opposite directions and so that the tread thereof may move over and off of the main rail, a rigid plate adjacent to one end of the switch-point rail, a sliding block between the rigid plate and the end of the switch-point rail adjacent thereto, a crank-rod, means for operating the crank-rod, and 110 connections between the crank-rod and the ends of the switch-point rail and between such crank-rod and the sliding block; whereby when the crank-rod is operated and the switch-point rails are moved over and onto the unbroken rail the sliding block is moved to lock the end of the switch-point rail which is adjacent thereto; substantially as described.

DANIEL GRUHLKEY.

In presence of—
G. C. STEBBINS,
HATTIE GRAY.
